NONREFILLABLE ATTACHMENT

Jacob W. Schieber, Scranton, Pa.

Application November 27, 1935, Serial No. 51,948

5 Claims. (Cl. 215—30)

This invention relates to a non-refillable attachment for bottles, jugs and containers, and is designed primarily for use in connection with bottles containing high grade liquors, wines, perfumes, etc., but it is to be understood that the attachment, in accordance with this invention, may be employed in connection with any type of container for which it is found applicable.

The object of the invention is to provide, in a manner as hereinafter set forth, an attachment of the class referred to which, when in anchored position with respect to a bottle, will prevent the surreptitious refilling of the bottle after the original contents of the latter have been discharged.

A further object of the invention is to provide, in a manner as hereinafter set forth, an attachment, for the purpose referred to, which will permit a steady discharge, with no surging action, of the contents of a bottle when the latter is tilted from the vertical to beyond the horizontal, and further will prevent discharge from the bottle when the latter is disposed in a vertical inverted position.

Further objects of the invention are to provide, in a manner as hereinafter set forth, a non-refillable attachment for bottles, jugs and containers which is simple in its construction and arrangement, readily installed with respect to the neck of a bottle, jug or container, strong, durable, compact, thoroughly efficient in the use intended thereby, and comparatively inexpensive.

With the foregoing and other objects in view, the invention consists of the novel construction, combination and arrangement of parts as will be hereinafter more specifically described and as are illustrated in the accompanying drawings wherein is shown an embodiment of the invention, but it is to be understood that changes, variations and modifications may be resorted to which fall within the scope of the invention as claimed.

In the drawings:

Figure 1 is a vertical sectional view of the attachment installed relative to the neck of a bottle,

Figure 2 is a vertical sectional view of the attachment installed relative to the neck of a bottle, taken at right angles to the showing of Figure 1,

Figure 3 is a section on line 3—3, Figure 1,
Figure 4 is a section on line 4—4, Figure 1,
Figure 5 is a front elevation of the bottle neck,
Figure 6 is a top plan view of the lower valve
55 seat forming member,

Figure 7 is a sectional plan of the form of globular valve employed,

Figure 8 is a view looking towards the inner face of one of the two like sections of the attachment when the section is tilted,

Figure 9 is a vertical sectional view of a modified form of attachment installed relative to the neck of a bottle, and

Figure 10 is a vertical sectional view of still another modified form of the attachment installed relative to the neck of a bottle.

Referring to the drawings, 12 and 13 denote, respectively, the breast and neck of a bottle in Figures 1, 2, 5, 9, and 10. The neck 13 is of cylindrical contour and formed of an outer and an inner part 14, 15, respectively. The parts 14, 15 are of different outer diameters. The part 14 is of smallest outer diameter. The junction of the two outer diameters form the neck 13 with a peripheral annular flange 16. The inner diameter of neck 13 is uniform. Positioned on the mouth edge 17 of the neck 13 is a resilient washer or gasket 18 of a width slightly greater than the width of edge 17 and extends inwardly and outwardly with respect to part 14 of the neck 13. The outer face of part 14 of neck 13 is formed with a pair of oppositely extending diametrically disposed bayonet-shaped grooves opening at edge 19.

The attachment includes a pair of oppositely disposed sections 21, 22 of like form, with this exception, that section 21 is formed in its inner face with a pair of spaced oppositely disposed like grooves 23, 24 of tortuous form and that section 22 has its inner face formed with a pair of spaced oppositely disposed ribs 25, 26 which engage in the grooves 23, 24, respectively, and correspond in contour to that of the grooves. The grooves are of the same length as that of the ribs and extend from the top edge of the section in which they are formed to a point adjacent the inner end of said section. Each section comprises a one-piece body 27 of the desired length and width and formed with a flat inner face portion 28 for the major portion of its length. The grooves 23, 24 are formed in the flat inner face portion 28 of the section 21. The ribs 25, 26 are formed on a flat inner face portion of the section 22. The body 27 of each section includes a forward end part 29, a pair of intermediate parts 30, 31, a rear end part 32, and a suspended inner part 33. The part 29 is semi-cylindrical in cross-section. The part 30 is substantially of rectangular contour in cross-section. The part 28 is of frusto-tapered contour and substantially rectan-

gular in cross-section. The part 32 is semi-cylindrical in cross-section but its body is of less thickness than the body of part 39. The part 33 is semi-circular in cross-section and merges at 5 its forward end into the rear end of the part 28. The part 33 is of greater length than and is spaced from the inner face of part 28. The part 33 is of a width to extend into the neck 13 to a point below the shoulder 16. The grooves 23, 24 10 are formed in the parts 29, 30 and 31 of the section 21 in proximity to the edges of such parts. The ribs 25, 26 are formed in the parts 29, 30 and 31 of the section 22 and are arranged in close proximity to the edges of said parts. Each groove 15 includes a forward straight branch 34, an intermediate straight branch 35, a rear outwardly inclined branch 36, an outwardly extending forward branch 37 which merges into the branches 34 and 35, and a rear inwardly extending branch 20 38 which merges into the branches 35 and 36. The part 31 of section 21 includes a rear edge portion 39 to which the branch 36 extends. Each rib includes a forward end straight stretch 40, an intermediate straight stretch 41, an inclined 25 rear end stretch 42, an outwardly extending forward intermediate stretch 43 which merges into the stretches 40, 41, and an inwardly extending rear intermediate stretch 44 which merges into the stretches 41, 42. The part 31 of the section 30 22 includes a rear edge portion 45 with which is flush the rear end of stretch 42. The rear edge portion 39 of the part 31 of the section 21 is arranged inwardly with respect to the outer face of such section and laterally disposed with respect to the part 33 of section 21. The rear edge portion 45 of the part 31 of the section 22 is arranged inwardly with respect to the outer face of such section and laterally disposed with respect to the part 33 of section 22. The stretches of the ribs 40 snugly engage in the branches of the grooves. The edge portions 39 and 45 constitute inwardly arranged annular shoulders.

The part 29 is of less width than the part 30. The part 31 gradually decreases in width from 45 its point of jointure with part 32 to its point of jointure with part 30. The major portion of the length of part 31 is less than the width of part 30 but greater than the width of part 29. The width of part 32 is less than that of the part 30. 50 The width of part 33 is less than that of parts 30, 31 and 32.

Each section is formed lengthwise thereof with an outer cavity 46 of semi-circular cross-section which is arranged in a portion of part 30 and extends throughout part 31. The cavity 46 is open at 55 its rear end and closed at its forward end, as at 47. The cavity 46 consists of a portion 48 gradually decreasing in width to the closed end 47 and a portion 49 of uniform width, of less 60 length than and merging at its forward end into the rear end of the portion 48. Each section is formed lengthwise thereof with an inner cavity 50 of semi-circular cross-section which is arranged completely in part 33. The cavity 50 is 65 open at its rear end and partly closed at its forward end, as at 51. The cavity 50 consists of a portion 52 gradually decreasing in width to the closed end 51 and a portion 53 of uniform width, of less length than and merging at its forward 70 end into the rear end of the portion 52. The cavity 50 is of less length than the part 33 and has its rear end flush with the rear end of part 33. The wall part of the portion 49 of the cavity 46 is formed with a semi-circular groove 54. The 75 wall part of the uniform portion 53 of the cavity

51 is rabbeted, as at 55, and formed with a semi-circular groove 56.

Each section is provided with a pair of oppositely extending outer tortuous grooves 57, 58 and a pair of inner oppositely disposed tortuous grooves 59, 60. The grooves 57, 58 are of like form and each consists of an outer end branch 61, an inner end branch 62, an outer intermediate branch 63, a rear intermediate branch 64, and an inner intermediate branch 65. The rear end of the branch 10 61 merges into the outer end of the branch 63. The rear end of the latter is closed. The rear end of the branch 64 is closed. The branch 65 establishes communication between the forward end of the branch 64 and the branch 63 intermediate the 15 ends of the latter. The branch 62 opens into the cavity 46 and establishes communication between the cavity intermediate its ends and between the branch 64 intermediate the ends of the latter. The branch 61 at its forward end opens into the 20 part 29. The branches 61, 63 and a portion of the branch 64 are arranged in the part 30. The remaining portion of the branch 64 is arranged in the part 31. The branch 62 is arranged in the parts 30 and 31.

The grooves 59 and 60 are of like form and are oppositely disposed and each consists of an inwardly inclined branch 65 closed at its rear end and an inner branch 66 which opens into the cavity 50 intermediate its ends and also opens into the branch 65 intermediate its ends. The branch 65 extends forwardly of the cavity 50 and merges into a rectangular recess 66a formed in the forward end of the part 33. The passages in cross-section are of curved contour. The closed ends 35 of the branches 65 of the grooves 59, 60 extend rearwardly with respect to the branches 66 of the said grooves.

The part 30 of each section is formed centrally with a socket 67. The part 31 of each section in 40 proximity to its rear end is formed with a pair of spaced aligning sockets 68, 69. The part 32 of each section in proximity to its rear end is formed with a pair of diametrically opposed lugs 70 on its inner face.

The sections 21 and 22 are secured together in abutting relation by holdfast elements 71 of a form capable of engaging in the sections when said elements are in holdfast position. When the sections 21 and 22 are arranged in abutting relation, the mouth of the socket 67 of section 21 registers with the mouth of the socket 67 of section 22, the mouth of the socket 68 of section 21 registers with the mouth of the socket 68 of section 22, and the mouth of the socket 69 of section 55 21 registers with the mouth of the socket 69 of section 22. A holdfast element 71 is mounted in each pair of aligning sockets, by way of example, as illustrated in Figure 2 for securing the sections in abutting relation. When the sections 21, 22 are secured together, the ribs 25, 26 engage in the grooves 23, 24 respectively; the grooves 57 of the sections 21, 22 register to form an outer tortuous tubular passage 72 for fluid discharge and for combined air intake and fluid discharge. The 60 passage 72 opens at its forward end into an outlet 73 provided by the inner faces of the parts 29 of the sections when said sections are in abutting relation. When the sections 21, 22 are secured together, the grooves 58 of the sections 21, 22 register to form an outer tortuous tubular passage 74 for fluid discharge and for combined air intake and fluid discharge. The passage 74 opens at its forward end into the outlet 73. The latter is normally closed by a removable stopper 75. When 75

the sections 21, 22 are secured together, the cavities 46 of said sections register to provide an outer valve chamber 76 for a globular valve 77 and a resilient disc valve 78. When the sections 21, 22 are in abutting relation, the cavities 50 thereof register to provide an inner valve chamber 79 for a ball valve 80 and a resilient disc valve 81. When the sections 21, 22 are secured together, the grooves 59 thereof register to form a rear tortuous tubular passage 82 for conducting liquid and for conducting combined air and liquid. When sections 21, 22 are connected together in abutting relation, the grooves 60 thereof register to provide a rear tortuous tubular passage 83 for conducting liquid and for conducting combined air and liquid. When the sections 21, 22 are secured together in abutting relation, the recesses 66^a of said sections register to provide a rectangular opening 66^b into which the passages 82, 83 open. When the sections 21, 22 are secured together in abutting relation, the semi-circular grooves 54 thereof register at their ends to form an annular forward groove. When the sections 21, 22 are secured together in abutting relation, the rabbets 55 thereof register to form an annular rabbet and the semi-circular grooves 56 thereof register at their ends to form an annular rear groove. The part 33 of each section is formed with a semi-circular groove 84 and said grooves 84, when the sections are secured in abutting relation, register to form a tubular passage 85 (Figure 2) for establishing communication between the valve chamber 79 and the rectangular opening 66^b provided by the registering of the recesses 66^a. The rear ends of the channels 12, 14 open into the valve chamber 76 at the opposite sides thereof and intermediate its ends. The rear ends of the channels 82, 83 open into the valve chamber 79 at opposite sides thereof and intermediate its ends.

40 The attachment includes a forward and a rear combined valve seat and holding member 86, 87, respectively of circular form. The member 86 consists of a disc 88 which is mounted in the forward annular groove provided by the grooves 54 of the sections. The disc 88 has a central opening 89 which communicates with the opening 66^b. Integral with the upper face of the disc 88 is a series of upstanding equi-distant spaced lugs 90 positioned inwardly adjacent the edge of disc 88 and bearing against the uniform portions 49 of the cavities 46 formed in the sections 21, 22. The lugs 90, in connection with the disc 88, form the member 86 of substantially cup-shaped contour. The lugs 90 are spaced outwardly adjacent to the edge of the wall of opening 89. The valve 78 is normally seated on the disc 88 between the lugs 90 and tends to normally close the opening 89. The valve 77 is seated on the valve 78 and is freely movable within the valve chamber 76. The diameter of the valve 78 is less than the distance between the lugs 90.

45 The member 87 consists of a disc 91 formed with an opening 92 which communicates with the interior of the bottle. The disc 91 is formed with a laterally disposed annular extension 93 which extends into the rear annular groove formed by the grooves 56 of the sections 21 and 22. The disc 91 abuts against the rabbets 55 of the sections 21 and 22. The intermediate portion of the disc 91 is of reduced thickness, as at 94, and upon which normally seats the valve 81. Formed integral with disc 91 is a series of equi-distant spaced upstanding lugs 95 which abut against the uniform portions 53 of the recesses 50 in the sections 21 and 22. The diameter of the valve

81 is less than the distance between the lugs 95. The valve 80 seats on the valve 81 and is freely movable in the valve chamber 79.

5 When the sections 21, 22 are secured together by the holdfast means 71, the parts 32 of said sections coact to form the attachment with an annular inner end which surrounds and is connected to the portion 14 of the neck by the coaction of the lugs 70 with the bayonet-shaped grooves 19. The edge portions 39 of the sections 10 21, 22, when the attachment is coupled to the neck, seat upon the washer or gasket 18. Prior to the coupling of the attachment to the neck the portion 14 of the neck, as well as the shoulder 16, is coated with suitable cementitious material 96 15 for the purpose of fixedly and permanently securing the attachment to the bottle neck. When the sections 21, 22 are secured together by the holdfast means 71, the parts 33 of said sections are brought into abutting relation and provide 20 an internal inner end part of circular cross-section which extends into and is disposed in concentric relation relative to the inner face of the neck of the container. The gasket 18 acts to seal the forward end of the space formed between 25 the abutting parts 33 and the inner face of the container neck.

30 The ball valves are of like construction and each consists of a metallic cover section 97 and a solid metallic core section 98. The latter is of 30 greater weight than that of the section 97.

35 The form shown in Figure 9 will include two like oppositely disposed interengaging sections (but one of said sections is shown) and designated generally at 99. These sections will be similar to 35 the sections 21, 22, with the exception that the outer grooves which coact to form the air intake and fluid discharge tortuous tubular passages will be of a different form with respect to the passages 57, 58, and that the inner grooves which 40 coact to provide the air and fluid conducting tubular passages will be of a different form with respect to the passages 59, 60. The section 99 corresponds to section 21. The other section, not shown, of the form illustrated by Figure 9, 45 will correspond to section 22. The sections of the modification will be of like form, but with this exception, that one section will be provided with a pair of grooves similar to the grooves 23, 24 of section 21 and the other section thereof 50 will be provided with a pair of ribs similar to the ribs 25, 26 of section 22. The description to follow with respect to section 99 is to be understood to apply to the section of the modification not shown.

55 The section 99 includes a pair of oppositely disposed outer grooves 100, 101 of like form and each includes an outer side wall formed of a series of stretches in angular relation. The said outer wall includes a short rear end stretch 102 which at its 60 outer end merges into the rear end of an inwardly extending upwardly inclined stretch 103. The latter merges at its outer end into the rear end of a straight stretch 104 of materially greater length than the stretches 102, 103. The stretch 65 104 merges at its outer end into the rear end of an inwardly extending upwardly inclined stretch 105 of greater length than stretch 103 and of less length than stretch 104. The stretch 105 at its outer end merges into the inner end of a laterally directed downwardly inclined stretch 106 of slightly less length than stretch 105. The lower end of stretch 106 merges into the rear end of an inwardly extending upwardly inclined stretch 107 of greater length than stretch 106. 75

The outer end of stretch 107 merges into the rear end of the outer end stretch 108 of said outer wall. The stretch 108 extends inwardly at an upward inclination and is of slightly greater length than stretch 107. The inclination of the latter is less than that of stretches 103, 105 and 108. The inclination of stretch 106 is less than that of stretch 105. The stretches 103, 105, 106, 107 and 108 are disposed at different angular relation with respect to the lengthwise median of section 99. The stretches 102, 104 are disposed parallel to the longitudinal median of section 99. Each outer groove includes a rear end wall 109. Each outer groove also includes an inner side wall formed with an opening 110 forwardly of wall 109. The opening 110 communicates with the recess 111. The inner side wall of each outer passage is formed of an inner and an outer section. The inner section of the inner side wall consists of a short straight stretch 112 extended forwardly from wall 109 and opposing in parallel spaced relation and of less length than stretch 102. The rear and front walls of opening 110 are indicated at 113, 114 and they are disposed at upward inclinations. The stretch 112 at its outer end merges into the outer end of the wall 113. The outer section of the inner side wall includes a rear end stretch 115 which extends inwardly at an upward inclination and at its rear end merges into the outer end of wall 114. The stretch 115 at its outer end merges into the inner end of a laterally directed downwardly inclined stretch 116 which at its outer end merges into the rear end of an inwardly extending upwardly inclined outer end stretch 117. The outer end stretches 117 of the grooves 100, 101 merge into each other at their outer ends. The combined intake and outlet of each outer groove is designated 118. The stretch 117 opposes the stretch 108 and a portion of stretch 107. The stretch 116 opposes a portion of stretch 106. The stretch 115 opposes the stretch 105 and a part of stretch 104. The lower portion of the latter, the stretch 103 and a part of stretch 102 opposes the opening 110. The stretches 115, 116 and 117 are disposed in different angular relations with respect to each other, and are also disposed in angular relation to the longitudinal median of section 99.

The inner grooves of section 99 are of like form, 50 oppositely disposed, and indicated at 119, 120. Each inner groove is formed in its inner side wall with an opening 121 which communicates with the recess 122. Each inner groove has its outer side wall 123 inclining upwardly from its rear to its forward end. Each inner groove has its inner side wall formed of a rear and a front section 124, 125, respectively, each inclining inwardly from its rear to its forward end. The rear end of section 124 merges into the outer end of the front 60 wall 126 of opening 121. The forward end of section 125 merges into the outer end of the rear wall 127 of opening 121. Each inner groove includes a rear end wall 128 which merges into the rear ends of the side wall 123 and section 125. The wall 123 opposes the sections 124, 125 and intermediate its ends opposes the opening 121.

The modification of the invention shown by Figure 10 resides solely in a different shape of the outer and inner grooves of each section of the attachment than that as shown in Figure 8. In Figure 10 the section 128 of the attachment which may correspond to sections 21, 22 or 99, but more particularly in contour to that of section 21 or 22, has the outer grooves formed therein, indicated at 129, 130, and the inner passage formed therein,

indicated at 133, 134. The inner grooves of section 128 are of the same form as the inner grooves shown in Figure 9.

The outer grooves 131, 132 are of like form and are oppositely disposed. Each of the outer grooves in section 128 includes an outer side wall which is formed of a rear end stretch 135 which is disposed at an inward inclination from its rear to its outer end, a laterally directed stretch 136 inclining downwardly from its inner to its outer end, a short vertical stretch 137, a horizontally disposed stretch 138, a vertically disposed stretch 139 and an inwardly extending forwardly inclined forward end stretch 140. The forward end of stretch 135 merges into the upper end of stretch 136. The lower end of the latter merges into the forward end of stretch 137. The rear end of stretch 137 merges into the inner end of stretch 138. The outer end of stretch 138 merges into the rear end of stretch 139. The forward end of stretch 139 merges into the rear end of stretch 140. The stretches 137, 139 are disposed parallel to the lengthwise median of section 128. The stretch 138 is disposed at right angles to stretches 137, 139 and at right angles to the longitudinal median of section 128. The stretch 140 overhangs the stretches 136, 137, 138. The stretch 139 is of greater length than stretch 138. The stretch 140 is of greater length than the other stretches, with the exception of stretch 135. The stretch 136 is of materially less length than one of the other stretches. The stretch 140 at its forward end merges into the inner end of the wall of the combined air intake and fluid outlet 141. The stretches 135, 136 and 140 are disposed in angular relation with respect to the other stretches and in angular relation with respect to the longitudinal median of section 128.

The inner side wall of said grooves 131, 132 is formed intermediate its ends with an opening 142 which communicates with the recess 143. The opening 142 has a forward wall 144 and a rear wall 145. The walls 144, 145 are horizontally disposed. The opening 145 forms the said inner side wall into an inner and an outer section. The inner section consists of a stretch 146 opposing and disposed at the same inclination as the stretch 135. The stretch 146 at its forward end merges into the outer end of the wall 145. The outer section of the inner side walls consists of a rear stretch 147 opposing a portion of, disposed at the same inclination as the stretch 135 and terminating at its rear end into the outer end of the wall 144, a horizontally disposed stretch 148, a rearwardly downwardly inclined stretch 149, a vertical stretch 150, a horizontal stretch 151, a vertical stretch 152, and an inwardly extending forwardly inclined stretch 153. The forward end of stretch 147 merges into the inner end of stretch 148. The outer end of stretch 148 merges into the upper end of stretch 149. The lower end of stretch 149 merges into the upper end of stretch 150. The lower end of stretch 150 merges into the inner end of stretch 151. The outer end of stretch 151 merges into the lower end of stretch 152. The upper end of stretch 152 merges into the rear end of stretch 153. The latter opposes stretch 140. The stretch 152 opposes stretch 139. The stretches 149 and 151 overhang stretches 138, 136. The stretch 150 opposes stretch 147. The stretch 148 aligns with the inner end wall 154 of the passage. The wall 154 connects the rear end of the stretches 135, 146 together. The stretches 146, 147, 149 and 153 are disposed in angular relation with respect to the 75

longitudinal median of section 128. The stretch 152 is disposed parallel to and the stretches 148, 151, as well as the wall 154, are disposed at right angles to the longitudinal median of section 128. 5 The inner grooves 133, 134 of section 128 are of the same form and arrangement as that of the grooves 119, 120 of section 99.

With reference to the form illustrated by Figure 9, the grooves 100, 101 of one section thereof 10 are adapted to register the grooves 100, 101 of the other section thereof to provide oppositely disposed tortuous independent tubular passages functioning in the same manner as the passages 72, 74. The grooves 119, 120 of the sections of the 15 form shown in Figure 9, are adapted to register to form inner tortuous independent tubular passages functioning in the same manner as the passages 82, 83. With reference to Figure 10, the grooves 129, 130 of the sections thereof are 20 adapted to register to form a pair of independent tortuous tubular passages functioning in the same manner as the passages 72, 74. Further with reference to Figure 10, the grooves 133, 134 of the sections thereof are adapted to register to form 25 independent tortuous tubular passages functioning in the same manner as the passages 82, 83.

If the bottle is tilted with respect to the horizontal to the right, the passage 72 constitutes a 30 fluid discharge passage and the passage 74 provides a combined fluid discharge and air intake passage. If the attachment is tilted with respect to the horizontal to the left, then the passage 74 forms a fluid discharge passage and the passage 72 provides a combined fluid discharge and air 35 intake passage.

The parts of the attachment are so arranged to 40 provide for discharge of the contents of the bottle after the attachment is disposed at an angle with respect to the horizontal and as the attachment, when extending downwardly, is moved towards the vertical, the flow decreases and completely stops when the attachment assumes an inverted vertical position. It is thought that the preventing of discharge from the bottle, when 45 the attachment is in an inverted position and vertically disposed, is due to an air-trap effect within the attachment. The tubular passages are of like form, oppositely disposed, of tortuous type having offset closed branches and so formed 50 as to prevent the passage of a wire or other implement to hold valve 78 off of its seat to sur- repetitiously refill the bottle.

The attachment is for employment in connection with any form of container having a neck or 55 an annular extended intake or filling member. The term container is also meant to imply a bottle or a jug. The term neck is also meant to imply an annular extended intake or filling member.

What I claim is:

60 1. In a non-refillable attachment for containers of the neck type, a structure formed of a pair of inner sidewise abutting oppositely disposed, inter-engaging sections and means within said sections at spaced points for anchoring them together in abutting relation, said sections having at their inner portions, respectively, oppositely disposed coacting outer parts to provide said structure with means for connecting it with respect to the container neck and oppositely disposed coacting inner parts to provide said structure with an extension disposed in concentric spaced relation to said means and for arranging in the container neck when said structure is connected to the neck, said sections being formed with 65 oppositely disposed coacting means on their inner

side faces to provide said structure respectively with inner and outer valve chambers in endwise aligned spaced relation, a pair of opposed, oppositely inclined, spaced inner tubular passages closed at their inner ends, a pair of oppositely disposed, spaced outer tortuous tubular passages closed at their inner ends, and a closable combined air intake and fluid outlet at its outer end, said inner valve chamber having its inner end wall formed with an opening for communication 10 with the container neck, said inner passages communicating with the inner valve chamber at opposite sides of the latter outwardly with respect to the closed inner ends thereof and communicating with each other at their outer ends and with 15 said outer valve chamber, said outer passages communicating with the outer valve chamber at opposite sides of the latter outwardly with respect to the closed inner ends thereof and opening at their outer ends into said combined air intake 20 and fluid outlet, a valve seat at the inner end of each of said chambers, freely movable valve means arranged in each of said chambers, and said inner chamber being in said extension.

2. The invention as set forth in claim 1 having 25 said inner chamber formed with an opening at the forward end communicating with the forward ends of said inner passages, and said outer chamber having its rear end formed with an opening communicating with the outer ends of 30 said inner passages and having its outer end closed to said outer passage.

3. In a non-refillable attachment for containers of the neck type, a structure having means for connecting it in encompassing and extended relation with respect to the neck of the container, 35 said structure being formed therein with outer and inner cavities arranged in endwise opposed spaced relation and each having its inner end open, a flanged cup-shaped axially apertured 40 member anchored in said structure at the open end of and extended into each cavity, said members coacting with the cavities to form inner and outer valve chambers and valve seats at the inner ends of the chamber, a resilient disc valve loosely mounted in each of said members, a globular valve loosely mounted on and providing a weighting means for each disc valve, said inner chamber for communication with the container neck, said outer chamber for communication with the atmosphere, said structure being provided therein with means in the form of spaced tubular passages 50 extending from opposite sides of the inner chamber for establishing communication between said chambers, and said structure being provided 55 therein with means in the form of spaced tubular passages extending from opposite sides of the outer chamber for establishing communication between the latter and the atmosphere.

4. The invention as set forth in claim 3 having 60 said structure formed with an extension for positioning within the container neck, the said inner cavity and the means for establishing communication between said chambers being arranged in said extension.

5. The invention as set forth in claim 3 having 65 said structure formed with an extension for positioning within the container neck, the said inner cavity and the means for establishing communication between said chambers being arranged in 70 said extension and said extension being of greater length than and arranged in concentric spaced relation with the means for connecting the attachment to the container neck.
